UNITED STATES PATENT OFFICE.

GOLDWIN SMITH, OF TAMPA, FLORIDA.

GAME.

Application filed August 29, 1927. Serial No. 216,192.

The invention relates to improvements in games particularly adapted to be played indoors similar to the mechanical base ball games described in my application for United States Patent, Serial Number 189,948, filed May 9, 1927.

The objects of the invention are to provide simple, economical and durable means, whereby the game of base ball may be practically simulated while the players thereof are indoors; to provide means whereby games by various rules may be played by players thereof who pay the owner or operator thereof for the privilege at places of public amusement, as carnivals, fair grounds, amusement parks, and the like; to provide means adapted to interfere with the normal movement of the ball, during playing of said game, for the purpose of enabling only the skillful and practiced players of the game to control the directional movement of said ball with the object in view of dislodging hinged characters or depositing the ball in pockets located in a stationary field whereby the most skillful and practiced player is usually adapted to earn the highest score and consequently is the successful participant of the several players of said game.

Other objects will be apparent from the hereinafter description.

The invention consists in the combination and arrangement of the various parts and elements, and in the details of the construction, as set forth and claimed.

In the drawings:

Fig. 1 is a plan view of the invention;

Fig. 2 is a section taken on the line 2—2 in Fig. 1;

Fig. 3 is a section taken on the line 3—3 in Fig. 1, with parts broken away; and

Fig. 4 is a section taken on the line 4—4 in Fig. 1, with parts broken away.

In the preferred construction of the invention I provide the circular table 1 having the centrally disposed upwardly extending projection 2 integrally formed therewith. From the projection 2 the top 3 of the table slopes upwardly and outwardly whereby when the table is in stationary position a sphere or ball is adapted, by the force of the gravitation, to be carried from any point on the table toward the projection 2.

The outer edge 4 of the table is curved upwardly for purposes hereinafter fully explained.

Fixed to the lower side 5, at the center of

the table 1, as by bolts 6, is the plate 7 having integrally connected therewith the downwardly extending spindle 8 having the bevel gear 9 suitably secured to its lower end 10. The lower end of the spindle extends downwardly from the gear and is received in the bearing 11 of the upper horizontally extending arm 12 of the U-shape support 13 having its lower horizontally extending arm 14 fixed, as by the bolts 15, to the circular plate 16 which is suitably secured to the inner ends 17 of the brace rods 18 having their outer ends 19 secured, as by thumb screws 20, to the horizontally extending flange 21 integrally formed with the vertical side walls 22 of the cylindrical casing or container 23 having its upper edges 24 curved inwardly.

For the purpose of providing manually operative means for rotating the table 1, the hand crank 25 is secured to the outer end 25 of the shaft 26 which protrudes through the hole 27 in the wall of the container. Suitably secured to the inner end 28 of the shaft 26 is the bevel gear 29 meshing with the bevel gear 30, whereby manual rotation of the crank 25 imparts rotary movement to the table 1.

The alignment of the shaft 26 is maintained as by the shaft being rotatably mounted in the spaced apart supports 30 having their lower ends secured, as by the bolts 30', to the adjacent brace rod 18.

Surrounding the table 1, and positioned with its inner edge 31 adjacent the outer edge 4 of the table 1, and in horizontal alignment therewith, is the rectangular stationary circlet or field 32 having the depressions or pockets 33, 34, 35, and 36 positioned at the corners of the outer edge 37 of the top plate 32' of the circlet. The pockets are separated by 90°, circumferentially of the table, to represent home plate, first base, second base, and third base, respectively, of the invention. The pockets are in a horizontal plane. Intermediate the pockets 33 and 34, 34 and 35, 35 and 36, 36 and 33, are the ridges 37', 38, 39, and 40 which extend from the outer edge to the inner edge of the circlet. The ridges are equi-distant elevated from the position of the pockets 33, 34, 35 and 36. The surface 41 of the circlet intermediate the ridges slope downwardly toward the respective pockets, as shown in Figs. 3 and 4, whereby a sphere or ball that is positioned at any point between the ridges 37' and 38, 38 and 39, 39 and 40, and 40 and 41, is adapted to be carried, by the force of gravitation, into the re-

spective pockets 34, 35, 36 and 32, located intermediate the ridges between which the ball is positioned. The ridges are spaced equidistant from the adjacent pockets.

5 The circlet is secured in position as by the flange 42, integral with the horizontally extending plate 43, being bolted to the inner surface of the walls 22 of the container 23, whereby the complete mechanism including 10 the circlet 32, table 1, gears 9 and 29, spindle 8, shaft 26 and brace rods 18 may be manually removed from the cylindrical container 23 after the thumb screws 20 are removed from threaded engagement with the flange 15 21 of the walls of the container, and the brace rods 18.

Hingedly connected with the outer edge portion 44, of the top 32', of the circlet are the spaced apart characters 45 which may be 20 animals, miniature automobiles and controllers of traffic, various colored balls, pins, valuable merchandising articles, or letters of the 25 alphabet or numerals, where the game is utilized for purposes of educating children, and the like. A ball or sphere positioned upon 30 the table 1 is adapted by the centrifugal force of the rotating table to be forced outwardly of the table and over the curved edge 4 onto the circlet 32 and into one of the pockets 33, 34, 35 or 36, or the ball may contact one or 35 more of the characters 45 knocking them from the upward to the downward position after which the ball is adapted to pass between the circlet and the walls of the container upon the plate 43 of the circlet from where the ball is adapted to roll down the inclined surface of the plate through the hole 46 into the compartment 47 of the bin 48 from where the players may obtain the balls 40 through the hole 48' in the wall of the container. The plates 32 and 43 are integrally 45 connected with the cylindrical support 48, whereby the ball is guided on one side by the walls of the container, and on the other side by the support 49 to the compartment 47 which is located at the point of the lowest elevation of the plate 43.

It is desirable to position the crank 25 and the opening 48', in the container 23, in close 50 proximity to each other for the particular reason that an important advantage of the invention is that numerous players may seat themselves around the game and after one of the players has completed his turn of operating 55 the crank, the casing 23 may be rotated upon its legs 50 (secured to the bottom of the casing) to position the crank in close proximity to the person whose turn is the next to play, or if desirable the casing may be stationary and the players may each operate the 60 crank at the same position.

If desirable, suitable manually operative mechanism may be provided for delivering one or more of the balls from the bin 48 upon 65 the insertion of a coin in a suitable mechanism,

whereby the game may be played by persons who pay for the privilege without the necessity of the owner supplying an attendant to operate the game.

The playing of three balls may represent 70 an inning for one player whereby the usual nine innings of a ball game will comprise playing a total of twenty-seven balls by each player to complete a game. It is quite apparent that the game may be played as a miniature base ball game or by numerous rules and regulations which may be devised from time to time by the manufacturers, sellers and users of the game.

An important object of the players of the 80 invention is to manipulate the crank 25 so that a ball will leave the edge 4 of the table 1 at a point where the ball will be carried into one of the pockets 33, 34, 35, or 36, or contact one or more of the characters 45. 85 Suitable rules may be formulated for counting the points gained by players who are successful in manipulating the crank 25 to cause the balls to knock down the characters 45 or enter the pockets. At the completion of a 90 game the points gained by a player are added and his being the successful participant of the game, of course, depends upon whether he has earned a greater number of points than all other players.

The projection 2, at the center of the table 1, as well as the curved edge 4 of the table interferes with the normal movement of the ball, whereby skilled players are more adept than inexperienced persons in gaining high 100 scores. The ball may be placed upon the table while the latter is in motion, or while the crank 25 is stationary. Suitable means, as properly positioned magnets, or other mechanism, may be employed for replacing the 105 characters from the downward position to the upward position.

While I believe that the form of the invention illustrated in the drawings and referred to in the above description, as the preferred 110 embodiment, is the most efficient and practicable, yet realizing that the conditions concurrent with the adoption of the device will necessarily vary, I desire to emphasize the fact that changes may be resorted to, when 115 required, without sacrificing any of the advantages of my invention.

What I claim as new and desire to secure by Letters Patent is:

1. In a device of the class described, a rotatable table having its outer edge curved upwardly, an upwardly extending projection at the centrally disposed top of said table, a stationary field surrounding the table and having a plurality of pockets therein to receive said ball, characters surrounding said field and movably mounted thereon, and manually operative means to rotate the table and said projection to drive said ball toward and into said field, whereby skill of the play- 120 125 130

ers of said game determines whether said ball dislodges said characters or is received by one of said pockets.

2. In a device of the class described, a rotatable table, having its outer edge curved upwardly, a field surrounding the table and having a plurality of pockets therein, a plurality of characters hingedly connected with the outer edge of said field and manually operative means to rotate said table.

3. In a device of the class described, a rotatable table, a rectangular stationary circlet surrounding the table and having a plurality of equi-distant spaced apart pockets in its corners, a plurality of characters movably connected with the outer edge of said field and manually operative means to rotate the table.

4. In a device of the class described, rotatable means having an upwardly extending projection integral therewith, a field surrounding said means and having pockets therein, a plurality of hinged characters at the outer edge of said field and manually operative means to rotate said first mentioned means, whereby said ball is adapted to be driven from said first mentioned means toward said field, substantially as and for the purposes specified.

5. In a device of the class described, a rotatable table, a projection at the top of said table, a stationary field surrounding said table and having a plurality of pockets at its outer edge to receive said ball, a plurality of spaced apart characters surrounding said circlet except at points adjacent said pockets, manually operative means to rotate the table and said projection to drive said ball toward and into said field whereby the skill of the players of the game determines whether said ball is received by one of said pockets or engages one or more of said characters.

6. In a device of the class described, a rotatable table, a stationary field surrounding said table and said field having a plurality of pockets therein, a plurality of characters around said field except at the location of said pockets and hingedly connected with the outer edge of said field, manually operative means

to rotate said table to prevent movement to 50 said ball to the center of said table.

7. In a base ball game, a container, brace rods fixed to said container, a plate fixed to the inner ends of said rods, a support fixed to said plate and having a bearing therein, a circular table having a projection at its center and having its surface sloping downwardly towards said projection, a spindle having its lower end rotatably mounted in said bearings, the upper end of said spindle fixed to the center of said table, a manually operative crank, gearing connections between said crank and said spindle, whereby rotation of said crank is adapted to rotate said table, a circlet around said table and having a plurality of pockets in its outer edge, the surface of said circlet adjacent said pockets sloping downwardly there-to, a plurality of characters on said circlet except at said pockets, a casing surrounding said circlet at points spaced apart therefrom whereby a ball driven from said table over said characters is adapted to drop between said casing and said circlet, a bin in said casing, and a trough under said pockets and sloping downwardly toward said bin, whereby balls driven between said circlet and said casing are received by said trough and directed to said bin.

8. In a ball game device, a rotatable table having a top sloping downwardly toward the center thereof, a projection at said center, a circlet surrounding said drum and having a plurality of pockets therein representing home plate, first base, second base, and third base, ridges in said circlet intermediate said pockets whereby the upper surface of said circlet adjacent said pockets slopes downwardly toward said pockets, a plurality of characters hingedly connected with said circlet, a casing surrounding said circlet, manually operative means to rotate said table whereby when said ball is placed upon the top of said table the manual operation of said means is adapted to cause said ball to roll toward said circlet and be carried into one of 95 said pockets, or engage one of said characters.

GOLDWIN SMITH.
